UNITED STATES PATENT OFFICE.

DANIEL KOPS, OF NEW YORK, N. Y.

BRASSIÈRE.

1,275,046.

Specification of Letters Patent. Patented Aug. 6, 1918.

Application filed May 11, 1918. Serial No. 233,832.

To all whom it may concern:

Be it known that I, DANIEL KOPS, a citizen of the United States, residing in the borough of Manhattan, city, county, and State of New York, have invented an Improvement in Brassières, of which the following is a specification.

This invention relates to a brassière and more particularly to that type of brassières which are so constructed as to be adjustable to position on the body of the wearer along the axillary lines of the garment as shown and described in Letters Patent No. 1,233,250, July 10, 1917, and Letters Patent No. 1,253,052, dated January 8, 1918. In the garments shown and described in these patents there are employed together with the front and rear members, lacing devices for adjustably connecting the parts of the garment along the axillary lines thereof, and also tie tapes which are secured to corresponding ends of the laces and adapted to be brought to the front of the garment and connected in order to adjust and secure the garment in position. In these structures however, the tie tapes are permanently connected to the laces so that in the use thereof there is no possible movement or adjustment between the points of connection of the tie tapes and laces, making it necessary as will be apparent, to connect the tie tapes to the laces in different positions to form different adjustments of the garment and even when so properly connected in any given case when the tie tapes are fixedly secured to the laces, no relative movement of the laces and the parts of the garment is permissible depending upon the movements of the body of the wearer when the garment is fitted thereon.

Now the object of my present invention is to provide a structure in which the connection between the tie tapes and the adjusting laces is automatically shiftable not only in adjusting the garment to position on the body of the wearer, but also permitting the shifting of the positions of these parts with the movements of the body of the wearer when the garment is adjusted to position thereon, as will be hereinafter more particularly described.

In the drawing:

Figure 1 is a perspective view illustrating the use of one form of my present invention.

Fig. 2 is an enlarged elevation of the inner side of the garment as illustrated in Fig. 1.

Fig. 3 is a perspective view illustrating the use of another form of the invention.

Fig. 4 is a view similar to Fig. 2 showing the inner side of the garment illustrated in Fig. 3, and

Fig. 5 is a plan view of the connecting member as employed in the form of garment shown in Figs. 3 and 4.

Referring to the drawing and particularly to Figs. 1 and 2, the garment comprising the present invention consists of a front member 10 which is continuous or undivided and is so shaped as to be adapted to act as a bust supporter, together with back members 11 and 12. The front member 10 may be made in sections indicated at 13, 14, and 15, and similarly the back member 11 may be made of sections indicated at 16 and 17 and the back member 12 of sections indicated at 18 and 19.

Along one upright edge on the front section 10, the same is provided with a reinforcing strip 20 suitably connected thereto and fitted with series of eyelets 21. The adjacent edge of the back section 11 is similarly provided with a reinforcing strip 22 fitted with a corresponding series of eyelets 23. Laces 24 are passed through the eyelets 23 and eyelets 21 and are preferably arranged in pairs as illustrated in the drawing, with one end of the members of each pair of laces terminating in the reinforcing strip 20, passing through and adjustable in eyelets 23 in the reinforcing strip 22 and terminating in loops 25 pass through a ring 26. At one end a tie tape 27 is also secured to the ring 26 and extends to the lower front portion of the garment. The ring 26 is of sufficient diameter to permit the free passage of the laces and to be slid able thereon so as to automatically shift to position in adjusting the garment to place as well as to be shiftable in the garment when the same assumes different positions on the body of the wearer due to the movements of the body.

In the same manner on the other side of the garment the opposite edge of the front member 10 is provided with a reinforcing strip 28 in which there is a series of eyelets 29. The adjacent edge of the other back member 12 is also fitted with a reinforcing strip 30 in which there is a similar series of eyelets 31. Laces 32 are threaded through the eyelets 31 and also through the eyelets 29 in a manner similar to that described in the corresponding parts on the other side of the garment. These laces 32 are passed through a ring 33 which corresponds with the ring 26 and one end of the tie tape 34 is also passed through and connected to the ring 33. The tie tapes 27 and 34 pass through tape holes 36 provided therefor in a reinforcing piece 35 secured to the lower front central portion of the garment, so that these tie tapes may be brought together and connected to one another in the adjustment of the garment to place on the body of the wearer.

The free end of the back member 11 is preferably fitted with a reinforcing strip 37 in which there are secured hooks 38 and similarly the free edge of the back member 12 is fitted with a reinforcing strip 39 in which there is a corresponding number of eyes 40 adapted to be engaged by the hooks 38 in order to connect the parts of the garment to one another at the back of the body of the wearer. Also as indicated in the drawing this brassière may be provided with shoulder straps 41 and 42 and with a tape 41' and a hook or buckle 42' by means of which the lower front portion thereof may be connected to a hook and eye member or other part of a corset or other garment, over the upper edge of which of course as will be understood, the lower edge of the brassière is adapted to fit when used.

Referring to Figs. 3, 4 and 5, and the form of invention therein illustrated, it will be seen that my present invention may be embodied in a garment which is divided at the front instead of at the back. In this structure the back member is indicated at 43 and the front members at 44 and 45. The back member 43 may be made in sections indicated at 46 and 47. One vertical edge of the back section in this structure is provided with a reinforcing strip 48 in which there is a series of eyelets 49. The adjacent edge 55 of the front member 44 is likewise fitted with a reinforcing strip 50 in which there is a corresponding series of eyelets 51. The laces 52 preferably employed in pairs are threaded through the eyelets 49 and also through the eyelets 51. These laces 52 are preferably arranged in pairs and the corresponding ends thereof are looped, each loop passing through an eyelet 53 provided in a connecting strap 54 to which at one end a tie tape 55

is secured. This tie tape 55 also passes 66 through a tape hole 56 in a reinforcing strip 57 at the front edge of the front member 44 to which there is also secured a series of eyes indicated at 58.

Similarly in the other side of the garment 70 the opposite edge of the back member 43 is provided with a reinforcing strip 59 in which there is a series of eyelets 60. The adjacent edge of the front member 45 is also provided with a reinforcing strip 61 in 75 which there is a corresponding series of eyelets 62. The laces 63 corresponding to the laces 52 are threaded through the eyelets 60 and 62 and the looped ends thereof through eyelets 64 in a connecting strap 65. One end of the tie tape 66 is secured to the connecting strap 65 and at its opposite end passes through a tape hole 67, provided in a reinforcing strip 68 fitted to the front edge of the front member 45 to which there is 85 also secured a series of hooks 69 adapted to engage with the eyes 58 to connect the parts of the garment at the front thereof.

It will now be apparent that in the adjustment of the garment, hereinbefore described, to place on the body of the wearer, the rings illustrated in the form of the invention shown in Figs. 1 and 2 or the connecting strap in the form of the invention shown in Figs. 3, 4 and 5, will automatically shift to different positions, and furthermore will permit the shifting of the parts of the garment and the laces adjustably connecting the same with the movements of the body of the wearer.

I claim as my invention:

1. A brassière comprising a back member, a front member, laces for adjustably connecting the said members along the axillary line of the garment with corresponding portions of the said laces being attached to one member and passing freely through the adjacent edge of the other member, and looped at opposite portions, a tie-tape, and a device secured to one end of the tie tape 110 and through which the said opposite portions of the said laces pass so as to make the device automatically shiftable to place in adjusting the parts of the garment to position on the wearer.

2. A brassière comprising a back member, a front member, laces for adjusting the said front and back members to position along the axillary line of the garment, the corresponding ends of said laces being secured to the front member at the edge thereof along the axillary line of the garment, and passing freely through the adjacent part of the edge of the back member and looped at their opposite ends, a tie tape, 120 and a device secured to one end of the tie-tape and through which the looped ends of the laces pass in such a manner as to make

the said device automatically shiftable to place in adjusting the parts of the garment to position on the wearer.

3. A brassière comprising a back member, 5 a front member, laces by which the front and back members are adjustably connected to one another along the axillary line of the garment, a tie tape, a ring through which

the said laces pass and to which one end of the tie tape is connected so that the ring is 10 automatically shiftable to position in adjusting the garment to place on the body of the wearer.

Signed by me this 3rd day of May, 1918.

DANIEL KOPS.
